UNITED STATES PATENT OFFICE.

ALBERT MORLEY, OF THREE OAKS, MICHIGAN, ASSIGNOR TO THE WARREN FEATHER-BONE COMPANY, OF THREE OAKS, MICHIGAN, A CORPORATION OF MICHIGAN.

INTERMITTENT FEED MECHANISM FOR SEWING-MACHINES.

1,168,536.

Specification of Letters Patent.

Patented Jan. 18, 1916.

Application filed January 8, 1914. Serial No. 810,925.

To all whom it may concern:

Be it known that I, ALBERT MORLEY, a citizen of the United States, and a resident of Three Oaks, in the county of Berrien and State of Michigan, have invented certain new and useful Improvements in Intermittent Feed Mechanism for Sewing-Machines, of which the following is a specification.

My invention relates to intermittent drive mechanism which is particularly adaptable, as for example in sewing machines, for driving a member for advancing the cloth through the sewing field.

Intermittent drive mechanisms which employ bodily traveling parts are very likely to fail and not operate properly beyond a certain speed. For example in the case of a sewing machine the cloth feeding member usually travels through an orbit during part of which the cloth is engaged and advanced by the member. It has been found that such bodily traveling member will not operate properly when the speed increases beyond a certain limit, this being probably due to inertia effect and vibration caused by the swiftly traveling body. Pawl and ratchet intermittent drive mechanism has also been used but the same defects have been found.

The main object of my invention is therefore to provide intermittent drive mechanism which is devoid of bodily traveling parts and which is more perfectly balanced to thereby reduce vibration, and which will operate with equal efficiency at any speed.

Although my improved intermittent drive mechanism may be used efficiently and advantageously on other machines I have found it of particular advantage and utility for controlling the cloth feed in a sewing machine and I shall therefore describe the invention in connection with such machine.

In the accompanying drawings Figure 1 is a rear elevational view of a sewing machine head, Fig. 2 is a plain view from plane 2-2, Fig. 1, Fig. 3 is a sectional view on plane 3-3, Fig. 1, Fig. 4 is a side elevational view of the sewing and feeding parts with the guide table in section, and Fig. 5 is a front elevational view of a spiral drive member.

The machine head structure shown comprises the base 10 overhung by the bracket 11 which carries at its end the guide lugs 12 and 13 for the needle bar 14 and presser foot bar 15. The base journals the main

shaft 16 carrying at its end the drive pulley 17 from which extends a crank pin 18 connected by connecting rod 19 with the crank end 20 of the rock shaft 21 whose other end is connected by suitable mechanism with the 60 needle bar 14 to effect vertical reciprocation thereof in the well known manner. The other end of the main shaft carries the rotary looper 22 which co-operates in the well known manner with a needle 23 secured in 65 the lower end of the needle bar, the needle reciprocating through an opening 24 in the guide table or plate 25 secured to the base 10. The lower end of the bar 15 carries a frame 26 from which extends the presser 70 foot 27 suitably connected therewith, this presser foot having the usual passageway 28 for the needle. To the rear of the needle line a feed mechanism is usually provided for advancing the cloth after each stitching 75 operation.

For the purposes of my invention the feeding members comprise a rotary drum 29 and a roller 30 held against the top thereof. The drum 29 has the points 29' and projects 80 upwardly beyond the top of guide plate 25 through opening 31 therein. The roller 30 is journaled in the bifurcated extension 32 on frame 26 carried by the presser foot bar, a spring 33 encircling this bar between the 85 collar 34 thereon and the top lug 12 of the machine frame serving to yieldingly hold the roller against the drum to securely hold cloth or other fabric to the drum in order that the cloth or fabric will be drawn along 90 and properly fed. Such engagement may be frictional or more positive by means of the points 29' on the drum.

The mechanism for intermittently rotating the drum 29 to rotate the drum only during 95 the periods that the needle is out of the cloth, is clearly illustrated. The drum is secured to the end of a shaft 35 journaled at its outer end in the base 10 and at its inner end in a frame or housing 10' extending into the 100 pocket or open space 36 in the base 10, through which the main shaft 16 extends. The inner end of the shaft 35 carries a skew gear 37 which meshes with a skew gear 38 mounted on the rear end of the transverse shaft 105 39 journaled in a bracket 40, the front end of this shaft 39 carrying a plane gear 41. The frame 10' also journals the main drive shaft 16 and within the frame this shaft carries a disk 42 from whose face extends a 110

gear ridge 43 with which the gear 41 meshes. This ridge extends spirally in order that when the disk is revolved the gear 41 and the feed drum are rotated. However, as the 5 drum should be rotated to advance the cloth only during the time that the needle is out of the cloth, the extent of the spiral is designed accordingly, the gear being then rotated to turn the drum only when the needle 10 is raised above the cloth and remaining at rest while the needle is passing through the cloth. The spiral ridge would therefore extend less than 360 degrees but in order to lock the gear against rotation or displacement 15 when it should remain at rest, the ridge at either of the ends 43^a or 43^b is extended along the arc of a circle centered at the axis of shaft 16 in order to fill out 360 degrees. Preferably, however, both these ends are 20 extended along circular arcs to overlap with a radial pitch displacement corresponding to the pitch of the gear 41. The gear then remains at rest and is rigidly locked against displacement when the circular sections of 25 the ridge are in coöperation therewith and is rotated only when the spiral section of the ridge coöperates therewith. One of the overlapping ends will also act to hold the gear in proper position to receive the on- 30 coming other end. The gear wheel and gear ridge are therefore always in mesh and the spiral section of the ridge causes the gear to be started without jar, the feed drum therefore gradually starting the cloth and 35 preventing injury thereto. Inertia effect is entirely eliminated as none of the parts travel bodily, the feed drum rotating on its axis and the gear ridge and gear wheel likewise rotating on their respective axes, and 40 the balance is perfect. The machine can therefore be driven at any speed and the cloth feed mechanism will under all conditions operate smoothly, accurately and efficiently. Any peripheral travel of the feed 45 drum can be obtained by proper design of

the spiral pitch, and the duration of such travel can be made anything by properly designing the length of the spiral ridge, and such travel of the drum can be timed with reference to the movements of the needle 50 by rotationally adjusting the disk 42 on the drive shaft 16. The mechanism also comprises a minimum number of parts which can be readily kept in order.

I do not desire to be limited to the exact 55 construction and arrangement shown and described as there may be changes and modifications which would still come within the scope of the invention.

I claim as follows:

In a sewing machine, the combination with a knurled feed drum, of a roller, a presser foot carrying said roller and said roller co-operating with said feed drum to hold fabric therebetween, a shaft on which the feed drum is secured, a skew gear on said shaft, a transverse shaft and a skew gear thereon meshing with the skew gear on the feed drum shaft, a plane gear on said transverse shaft, a main driving shaft and a disk thereon, said disk having a gear ridge extending from one of its faces and around its axis, said ridge being continuous with its ends overlapping and pitch displaced in correspondence with the pitch of said gear, said 70 overlapping ends extending in the arcs of circles and the remainder of said ridge continually varying in radius whereby said feed drum will be rotated when said gear is in mesh with the varying radius section 75 of said ridge and will be locked against rotation when said gear is in mesh with the circular sections of said disk.

In witness whereof, I hereunto subscribe my name this second day of January, 1914. 80

ALBERT MORLEY.
